UNITED STATES PATENT OFFICE.

ARTHUR E. HANSEN, OF SEATTLE, WASHINGTON, ASSIGNOR TO YOUNG IRON WORKS, OF SEATTLE, WASHINGTON, A CORPORATION OF WASHINGTON.

TRUCK-BODY HOIST.

Application filed October 8, 1923. Serial No. 667,200.

The object of my present invention is to provide a simple arrangement whereby the power of a hydraulic hoist cylinder, for instance, can be transmitted to the dumping body of a truck to raise the latter.

More particularly it is my object to provide such hoist means which will operate with maximum power and minimum speed at the outset, when the load is heaviest, and which will gradually increase its speed as the body is raised and as the load grows less, due to the increased angle of the dumping body.

Another object is to provide a simple hoist means to be power actuated, as through a hydraulic hoist cylinder, which through simple cam means will communicate the power of the hydraulic hoist to the body to raise the latter.

Other objects, and those relating to structural details, can best be ascertained by a study of the following specification and claim, and of the drawings accompanying the same.

Figure 1 is in general a side elevation of my hoist, the view being taken substantially along the line 1—1 of Figure 2.

Figure 2 is a plan view of the hoist elements, the body and its pivot being omitted and portions of the hoist being shown in section.

Figure 3 is a detail section on line 3—3 of Figure 2.

In truck hoists, particularly those of the horizontal type, heretofore proposed, so far as I am aware, the power of the horizontal hydraulic hoist cylinder and the cross-head or traveler actuated thereby has been transmitted to the body through links or levers so arranged that when the maximum lifting effect is required, the mechanical advantage of the levers or links is the least. When the body is horizontal and it is desired to lift it, most previous underbody hoists known to me have been so arranged as to give, not the greatest lifting effect, but the greatest speed in lifting. This has been generally considered necessary, due to space limitations beneath the body, though generally with underbody hoists the body has been raised farther above the frame or chassis than in the case of vertical or end hoists.

By my invention an extremely simple underbody hoist is provided, which may be operated from a horizontal hydraulic hoist

cylinder beneath the body, and which will have the greatest lifting effect in starting to raise the load, and which will increase the speed of lifting as the body rises and as its dead weight load is, in consequence, decreased. Thus I employ the power of the hoist cylinder to best advantage, and place thereon stresses which are more nearly equalized throughout the dumping period, rather than a high initial stress to overcome the inertia of the load and to lift it the first few inches, and then a steadily decreasing stress.

My invention resides in the means which will operate upon any usual type of dumping body, as 1, mounted upon a suitable truck frame or chassis, as 2, to move it into and from dumping position, as by pivoting at 10 upon the frame, and which means is actuated to raise the body into dumping position through the medium of suitable or usual power mechanism, indicated by the hoist cylinder 3 mounted upon the frame and operating a traveler or cross-head 31; particularly my invention resides in the combination of such means with the body, frame, and power mechanism.

The body pivot 10 I have shown as positioned adjacent the rear end of the frame 2 and body 1. The exact form and position of this mounting is largely immaterial, and it might take a variety of forms other than the straight pivotal connection illustrated. It is only essential that the body be movable relative to the frame 2 by tilting in some manner. Likewise the exact form of the power actuating mechanism is immaterial, and the horizontal hydraulic hoist which has been shown as mounted upon the frame 2 beneath the body 1 is included only as illustrating a power mechanism which is common in the art. Any suitable power mechanism for actuating the traveler or cross head 31 may be employed.

For convenience I have provided a trackway 21 extending lengthwise of the frame members 2, and have provided trackway rollers 32 upon opposite ends of the cross head, by means of which the cross head or traveler 31 is permitted a sliding engagement and movement lengthwise of the frame 2. It will be noted that at each side of the frame I have provided two such trackways 21, slightly separated. A single trackway at each side might prove sufficient, and it

might be sufficient in some cases to have only one or a pair of these trackways centrally located, but in order to better distribute the load and to balance it, I have provided these 5 trackways and duplicate rollers 32 at each end of the cross head 31. An additional reason for providing such trackways, and for placing them below the level of the upper flange of the frame member 2, as best 10 shown in Figure 3 is to enable the rollers to be of larger diameter than if they ran directly upon the frame members 2. This reduces their angular speed and the friction in their bearings, and prolongs the life 15 and efficiency of all such parts.

By means of the construction so far described, by controlling the movement of fluid within the hydraulic hoist cylinder 3 in the usual manner, the cross head 31 connected to its piston rod 30 is moved lengthwise the frame 2, the trackway rollers 32 riding along the rails 21. Preferably the movement of the traveler 31, when it is desired to raise the body 1, is in a direction 25 from the front of the frame towards the body pivot 10 at the rear.

I provide means which are interposed between the traveler 31 as it slides rearwardly along the frame and the body 1, which 30 means is actuated by the movement of the traveler to raise the body. Such means is conveniently formed as a cam. The exact form or manner of connection of this cam with the body or with the traveler 31 may 35 be greatly varied. Essentially it constitutes a member having its under surface formed as a cam, generally convexly curved, as indicated at 40, this surface being engaged by the traveler 31, or by a cam roller 40 34 carried thereon, and this member 4, which has the cam surface 40 formed thereon, being operatively connected to the body so that as the traveler 31 traverses the cam surface 40 and raises it, the body 1 will be 45 raised.

I have found it preferable to form the member 4 as a hoist arm which is pivoted at 42 upon the frame 2 at a point in the vicinity of the body pivot 10. The free end of 50 the arm 4 extends forward from its pivot, and extends sufficiently above the frame 2 or the track 21 secured thereto to permit the roller 34 and the traveler 31 to lie beneath its cam surface 40. Its swinging end has 55 sliding engagement with the under surface of the body 1, and may be provided with a roller 41 traveling upon a trackway 14 on the under surface of the body.

The conformation of the cam surface 40, 60 in the form just described, wherein it is formed upon a pivoted hoist arm, is largely dependent upon the relative positions of the pivot 42 of the hoist arm and 10 of the body, and upon the line of movement of the traveler 31 with respect to such pivots. In the

form illustrated in Figure 1 the pivot 42 is somewhat forward of the body pivot 10 and below it, and the line of movement of the traveler 31, if extended, would intersect a line connecting the two pivots 10 and 42. 70 It will be evident that the relative positions of the pivots 10 and 42, and of the line of movement of the traveler 31 relative thereto, may be varied without departing from the scope of my invention. The two pivot 75 points might coincide, for instance.

It is my object in forming the cam surface 40 to so shape this surface that the initial lifting effect, that required to overcome the inertia of the load and to lift its dead weight until an appreciable angle with the horizontal is made, is the greatest. This necessitates, of course, that the speed of lifting or of angular movement of the body 1 be low at the start. However, as the angle of the body 1 increases up to and beyond the normal dumping angle, its load upon the hoist arm or upon the traveler 31 decreases. Hence it is my object to so shape the cam surface 40 that, starting from an initial low speed and high lifting effect, it 80 will change the rate of angular movement of the body 1, gradually increasing its speed, although decreasing its lifting effect. The increased speed is possible by reason of the decreased load referred to as the angle of the body increases, thus requiring less effort to lift it a given distance or through a given angular amount as the dumping progresses. 90

In the form shown in Figure 1, which is my present preferred form, when the pivots 42 and 10 and the traveler 31 are located in the relative positions shown, I have found that the body will begin to lift at very slow speed but with a large lifting effect from a given power input to the hoist cylinder 3, and the speed of lifting will increase gradually as the traveler 31 or the cam roller 34 travels along the cam surface 40. When parts reach the dotted line position of Figure 1 dumping will ordinarily have occurred. Here the lifting effect is not great, owing to the close approach of the cross head 31 to the pivot 42 of the hoist arm. However, as the load has been dumped and there is only the weight of the empty body 1 resting upon the hoist arm, the hoist cylinder 3 is at all times capable of sustaining and lifting the load placed upon it. In effect the action of the traveler 31 in lifting the load is as though a wedge were forced along the frame 2 and between it and a generally inclined surface upon the bottom of the body 2. 110

It will be understood that the structural details may be varied to suit the ideas of the designer. I have shown two frame bars and two tracks 21 at each side of the truck frame, as explained above, and have placed the arm 4 so that it will swing between the trackways 120

21. The cam roller 34, therefore, is placed between the two trackway rollers 32, although all three rollers at each end of the traveler 31 are pivoted upon this traveler. 5 Preferably also the cam roller 34 is slightly less in diameter than the two trackway rollers 32, and as the arm 4 rests upon the smaller central roller 34, its sides are engaged by the larger outside rollers 32 to steady it, and to take any side thrust therefrom and to transmit it directly to the frame 10 2. This can best be seen in Figure 3.

What I claim as my invention is:

In combination, a truck frame, a dumping body pivoted thereon, a pair of separated tracks at each side of the frame, a 15

hoist arm pivoted upon the frame and positioned between each pair of tracks, the free end of said arms having sliding engagement with the under side of said body, a power 20 actuated cross-head movable lengthwise of the frame, pairs of trackway rollers thereon movable along said pairs of tracks, and a cam roller between each pair of trackway rollers, and of less diameter, said cam rollers 25 each engaging the under side of a hoist arm and movable therealong as the cross-head is moved to raise and lower the hoist arm.

Signed at Seattle, King County, Washington, this 1st day of October, 1923.

ARTHUR E. HANSEN.
